CLAIM

I claim the ornamental design for a media player docking station for bathing unit or watercraft, substantially as shown and described.

DESCRIPTION

FIG. 1 is a perspective view of a media player docking station for bathing unit or watercraft according to a first variant of the design;

FIG. 2 is a front elevation view of the media player docking station for bathing unit or watercraft of FIG. 1;

FIG. 3 is a left side elevation view of the media player docking station for bathing unit or watercraft of FIG. 1;

FIG. 4 is a right side elevation view of the media player docking station for bathing unit or watercraft of FIG. 1;

FIG. 5 is a top view of the media player docking station for bathing unit or watercraft of FIG. 1;

FIG. 6 is a bottom view of the media player docking station for bathing unit or watercraft of FIG. 1;

FIG. 7 is a perspective view of a media player docking station for bathing unit or watercraft according to a second variant of the design; and,

FIG. 8 is a front elevation view of the media player docking station for bathing unit or watercraft of FIG. 7, the right and left side elevation views being identical to the views shown in FIGS. 3 and 4 and the top and bottom view being identical to the views shown in FIGS. 5 and 6.

The broken lines are used to show portions of the media player docking station for bathing unit or watercraft and form no part of the claimed design.
